COMBINED VEHICLE STEERING WHEEL AND
HORN RING

John T. McCreary, Chicago, Ill.

Application October 2, 1953, Serial No. 27,066

Term of patent 14 years

(Cl. D14—30)

To all whom it may concern:

Be it known that I, John T. McCreary, a citizen of the United States of America, residing at Chicago, in the county of Cook, State of Illinois, have invented a new, original, and ornamental Design for a Combined Vehicle Steering Wheel and Horn Ring, of which the following is a specification, reference being had to the accompanying drawing, forming part thereof.

Fig. 1 is a top plan view of a combined vehicle steering wheel and horn ring, showing my new design.

Fig. 2 is a view in side elevation of the combined vehicle steering wheel and horn ring of Fig. 1.

Fig. 3 is a view in front elevation of the combined vehicle steering wheel and horn ring of Fig. 1, and

Fig. 4 is a bottom view of the combined vehicle steering wheel and horn ring.

I claim:

The ornamental design for a combined vehicle steering wheel and horn ring, as shown.

JOHN T. McCREARY.
